UNITED STATES PATENT OFFICE.

WADE H. FOSTER, OF BAD AXE, MICHIGAN.

FOOTWEAR-VULCANIZER.

1,374,371.

Specification of Letters Patent. Patented Apr. 12, 1921.

Application filed May 5, 1919. Serial No. 294,755.

To all whom it may concern:

Be it known that I, WADE H. FOSTER, a citizen of the United States of America, residing at Bad Axe, in the county of Huron 5 and State of Michigan, have invented certain new and useful Improvements in Footwear-Vulcanizers, of which the following is a specification, reference being had therein to the accompanying drawings.

10 The invention relates to vulcanizers and refers particularly to vulcanizers for curing the treads of foot wear. One object of the invention is to provide a construction which is adapted to cure treads of different shapes 15 and sizes and, further, to provide means for engaging both the bottoms and sides of the treads and adapted for the passage of a hot fluid. Another object of the invention is the provision of an adjustable member adapted 20 to firmly engage the sides of the treads being cured and to conduct heat thereto; and further, in making this adjustable member hollow for the passage of a hot fluid. Other objects of the invention reside in the novel arrangements and combinations of parts as 25 more fully hereinafter set forth.

In the drawings:

Figure 1 is a top plan view of the vulcanizer embodying my invention;

30 Fig. 2 is a longitudinal section therethrough;

Fig. 3 is a transverse section therethrough;

Fig. 4 is a longitudinal section through a modified construction;

35 Fig. 5 is an end view;

Fig. 6 is a top plan view thereof;

Fig. 7 is a cross-section on the line 7-7 of 40 Fig. 4.

1 is the work support of hollow form and 45 having the inlet opening 2 near one end of its bottom wall 3 and the outlet opening 4 at the opposite end, the bottom wall 3 being downwardly-inclined from the outlet opening to the inlet opening to permit drainage

45 of any moisture collecting in the work support. 5 is a pipe connecting into the inlet opening 2, and 6 is a suitable valve for controlling the passage of the hot fluid through the pipe from its source (not shown). The

50 top of the upper wall 7 of the work support is preferably corrugated and is curved to correspond approximately to the curve of the sole of the foot wear. 8 are upwardly extending flanges extending around three sides 55 of the upper wall 7, and 9 is a yoke extending substantially centrally transversely of

the upper wall and secured to the work support as by being cast integral therewith. 10 is an adjustment screw threadedly engaging the yoke and adapted to force the foot-wear 60 into firm engagement with the top of the upper wall 7.

For the purpose of curing the edges of the treads, there is provided the U-shaped flexible, pliable, bendable member 11 having its 65 inner side preferably concave, this member being adapted to rest upon the upper wall 7 of the work support inside the flanges 8 and to adjustably engage the edges of the treads. Suitable means, such as the adjustment screws 12, are provided threadedly engaging the flanges 8 and extending therethrough to adjust the member 11 into firm engagement with the edges of the treads, rotatably mounted members 12' being provided 70 at the inner ends of the adjustment screws and adapted to engage the flexible member. This member will conduct heat from the upper wall 7 of the work support to the edges of the tread to cure the same but when 80 used in this manner, the effecting of the cure takes considerable time. To effect the cure in less time, the flexible member is formed hollow for the passage of a hot fluid conducted thereto by the pipe connection 13 extending between the outlet opening 4 of the work support and one end of the flexible hollow member 11. This pipe connection is 85 controlled by a suitable valve 14. The other end of the flexible hollow member 11 is connected into by a suitable pipe connection 15, through which the moisture drains, the upper wall 7 of the work support being downwardly inclined toward its rear end for this purpose. 95

16 is the foot wear inside which is positioned the last 17 having lower flanges 18 conforming to the shape of the sole of the foot-wear and having the upper flanges 19 located beneath and substantially conforming to the upper part of the foot wear. 20 is a pressure plate resting upon the upper part of the foot wear and adapted to be engaged by the adjustment screw 10 in the yoke for clamping the foot-wear in place. 100 For the purpose of preventing the flowing of the material in the sole of the foot wear while being cured, the beveled key 21 is provided, which is adapted to engage the transversely-extending groove 22 in the rear end 105 of the upper wall 7 of the work support, this key being of a length to fit between the

legs of the flexible hollow member 11. With this arrangement it is seen that the sole of the foot-wear being cured is completely surrounded on all its sides by the flexible hollow member 11 and key 21, and it lies between the upper wall 7 of the work support and the last 17.

As shown in Figs. 4 to 7 inclusive, illustrating a modified construction of vulcanizer, 23 is the hollow work support which is arranged substantially the same as the work support 1, shown in Figs. 1, 2 and 3. The work clamping means 24 is different, the construction being as follows: 25 and 26 10 are arms secured to the sides of the work support 23 near its opposite ends, these arms extending upwardly and inwardly and being secured to each other at their ends by suitable means, such as the bolts 27. 28 15 are parallel members secured to the arms 25 and 26 and suitably spaced from each other as by the spacer blocks 29. These parallel members extend longitudinally of the work support 23 and are slidably engaged 25 by suitable work clamping members for securing the work to the work support. As shown, 30 is a member slidably mounted upon the parallel members 28 and having the internal threads 31. 32 is a bushing 30 having the external threads 33 adapted for rotative engagement with the threads 31. This bushing is provided with internal interrupted threads 34 having the diametrically opposite spaces 35 between their ends. 36 35 is a stem provided with interrupted threads 37 adapted to slide longitudinally through the spaces 35 and to engage and lock with the threads 34 upon the bushing when the stem is rotated with respect to the bushing. 40 By means of this construction, the work clamping means may be readily moved longitudinally of the work support and the work engaging stem may be longitudinally slid into engagement with the work and 45 then rotated with respect to the bushing when the interrupted threads will engage with each other and lock. Upon further turning of the stem, the bushing rotates within the member slidably engaging the slot, thereby tightening the stem against the work to clamp the work against the work support.

For the purpose of providing a better heat conducting contact between the pliable member 38 and the upper wall of the work support 23, the outer side wall of the pliable member 38 is inclined upwardly and inwardly and the swivel heads 39 upon the adjustment screws 40 are wedge-shaped so 55 that upon forcing the adjustment screws inwardly against the pliable members 38, they will have a wedge action upon the members 38 and force the latter into good heat conducting contact with the upper wall of the 60 work support.

For the purpose of preventing the escape of the material while it is being cured, the stop 41 is provided at the end of the work support 23. This stop slidably engages the end and is held in place by means of the 70 strips 42 secured to the work support. In order to adjust the stop upwardly, the thumb screw or other suitable means 43 is provided threadedly engaging the bracket 44 upon the end of the work support and adapted to 75 engage the stop 41, this stop being provided with a vertically-extending slot 45 which is engaged in by the pin 46 upon the work support.

If desired, sand may be placed in the foot 80 wear or article to be cured instead of the usual inner last. The stem 36 of the work clamping member will then engage a plate upon the sand for retaining the sand in place.

85

Although I have shown only vulcanizers for the soles of foot-wear, it is to be understood that the same arrangement shaped for vulcanizing heels of foot-wear can be used.

The term "tread" as used in this application is intended to refer to that part of the foot wear engaging the ground and includes the sole and heel of the foot-wear.

90

From the above description it will be readily seen that I have provided a simple 95 construction of vulcanizer which is adapted to vulcanize different sizes and shapes of treads of foot wear, due to the fact that the member engaging the sides or edges of the treads is adjustable, so that it will be in firm 100 engagement with these edges. Furthermore, the construction is such that heat is directly conducted into the bottom and sides or edges of the treads and, moreover, from members through which hot fluid, such as steam 105 passes. Also means is provided for preventing the escape of the material while being cured.

I claim—

1. In a vulcanizer, the combination with 110 a hollow work support, adapted for the passage of a hot fluid, of a pliable hollow member engaging the work and also adapted for the passage of a hot fluid.

2. In a vulcanizer, the combination with a 115 hollow work support, adapted for the passage of a hot fluid, of an adjustable hollow member engaging the work and also adapted for the passage of a hot fluid, and means for adjusting said hollow member to engage 120 the work.

3. In a vulcanizer, the combination with a hollow member having a surface adapted to be engaged by the work, of a hollow member upon said surface, adjustable to engage the 125 sides of the work, both of said hollow members adapted for the passage of a hot fluid.

4. In a vulcanizer, for foot wear, the combination with means adapted for the passage of a hot fluid for directly engaging the 130

bottom of the tread of the foot wear, of means adapted for the passage of a hot fluid for directly engaging the edges of the tread of the foot-wear.

5. In a foot-wear vulcanizer, the combination with a hollow member having a surface against which the tread of the foot-wear rests, said member adapted for the passage of a hot fluid, of a second hollow member 10 adjustably engageable with the edges of the tread of the foot-wear, said second member adapted for the passage of a hot fluid, and means upon said first-mentioned hollow member for adjusting said second hollow member.

6. In a vulcanizer, the combination with a hollow member having an inlet opening for steam near one end and an outlet opening at the opposite end, the lower wall of said 20 member being inclined downwardly to said inlet opening and the upper wall being shaped to conform to the work mounted thereon, upwardly extending flanges upon said member, a flexible hollow member resting upon said first-mentioned member inside said flanges, said flexible hollow member adapted to engage the sides of the work, adjustment members engaging said flanges and adapted to engage said flexible hollow member 30 to clamp the same against the work, means for clamping the work upon the first mentioned hollow member, and connections extending from the outlet opening in said first-mentioned hollow member to said pliable hollow member.

7. In a foot-wear vulcanizer, the combination with a hollow member having a surface against which the tread of the foot-wear rests, said member adapted for the passage 40 of a hot fluid, of a second hollow member adjustably engageable with the edges of the tread of the foot-wear, hollow connections between said hollow members, means upon the first-mentioned hollow member for adjusting said second hollow member, and means for preventing the flow of the tread of the work when heated.

8. In a vulcanizer, the combination with a work support adapted to be heated, of a 50 pliable member in heat conducting contact with said work support and work.

9. In a vulcanizer, the combination with a work support adapted to be heated, of a pliable member in heat conducting contact 55 with said work support, and means for ad-

justing said member into heat conducting contact with the sides of the work.

10. In a vulcanizer, the combination with a work support adapted to be heated, of a member movable transversely of said support, a rotatable member for clamping the work to said support mounted in said transversely movable member, and means permitting of the longitudinal sliding movement of said clamping member to advance the 65 same into engagement with the work.

11. In a vulcanizer, the combination with a work support adapted to be heated, of a member located above said support, a connection between said support and member 70 provided with a longitudinally extending slot, slidably engaged by said member, a rotatable member for clamping the work to said support and mounted in said first mentioned member, and means permitting of the 75 longitudinal sliding movement of said clamping member to advance the same into engagement with the work.

12. In a vulcanizer, the combination with a work support adapted to be heated, of a 80 clamping support provided with a longitudinally extending slot, a member slidably supported in said slot and having internal threads, a second member having external threads 85 engageable with internal threads and interrupted internal threads, and a stem engageable with the work for clamping the same to said work support, said stem having interrupted external threads slidably longitudinally between said first mentioned interrupted threads and adapted to engage and lock with the same when said stem is rotated relative to said second member.

13. In a vulcanizer, the combination with a work support adapted to be heated, of a 95 pliable member in heat conducting contact with said work support, and means upon said work support for adjusting said pliable member to engage the work.

14. In a vulcanizer, the combination with 100 a hollow work support adapted to directly engage the work and also adapted for the passage of a hot fluid, of a pliable member in heat conducting contact with said work support and surrounding the work, and 105 means for adjusting said member inwardly upon said work and against said work support.

In testimony whereof I affix my signature.

WADE H. FOSTER.
